UNITED STATES PATENT OFFICE.

CLAUDE NUTTER, OF MONTESANO, WASHINGTON.

INCUBATOR-HEATER.

1,242,230.

Specification of Letters Patent. Patented Oct. 9, 1917.

Application filed February 9, 1916. Serial No. 77,214.

To all whom it may concern:

Be it known that I, CLAUDE NUTTER, a citizen of the United States, residing at Montesano, in the county of Grays Harbor 5 and State of Washington, have invented certain new and useful Improvements in Incubator-Heaters, of which the following is a specification, reference being had to the accompanying drawings.

10 This invention relates to incubators, and more particularly to the heaters therefor.

The general object of my invention is the provision of a very simple heater for this purpose whereby both water and fresh air

15 may be heated by the same lamp or heating appliance and carried in and circulated through the incubator.

A further object of my invention is the provision of a very simple, cheaply made 20 construction of this character wherein the heat from the lamp fumes is caused to assist in heating the fresh air and water entering the incubator but is prevented from itself entering the incubator.

25 Another object is the provision of a device of this character which may be readily taken apart for cleaning or repairing and as readily assembled.

Other objects will appear in the course of 30 the following description.

My invention is illustrated in the accompanying drawings, wherein:

Figure 1 is an elevation of my improved heater in applied position;

35 Fig. 2 is a vertical sectional view through the heater;

Fig. 3 is a cross sectional view on the line 3—3 of Fig. 2;

Fig. 4 is a sectional view on the line 4—4

40 of Fig. 2.

Referring to these drawings, 10 designates a lamp casing which is made of sheet metal and which is cylindrical in form and into which the chimney 11 of the lamp is

45 adapted to be projected as illustrated in Fig. 2. The top of the lamp casing 10 is closed by a septum 12 which also forms the bottom wall of a water tank 13. From the water tank at its upper end extends an up-

wardly inclined water pipe 14 which leads into the incubator and may be there coiled or otherwise formed to provide for a circulation of hot water for heating the interior of the incubator. Surrounding the casing 10 and in spaced relation thereto is a casing 15 or shell. Extending from the up-

per end of this shell and surrounding the water pipe 14 is an air pipe 16 which also leads into the incubator. Mounted upon the upper end of the water tank 13 is the 60 annular spacing member 18 which is perforated at 19 and which is disposed between the top of the tank 13 and the top of the shell or casing 15. The air flue or pipe 16 is preferably rectangular in cross section. 65

The lower end of the space between the casing 15 and the casing 10 is closed by a perforated septum 20 through the perforation of which fresh air may enter the space 21 between the casing 15 and the casing 10. 70

Surrounding the casing 15 is an outer casing 22 which extends concentrically around the casing 15 as shown in Fig. 3 and then is deflected to form the two side walls 23 and 24 which extend parallel to the pipe 75 16 and in approximate contact therewith. The outer extremity of these walls is flanged as at 25. The space 22^a between the outer wall 22 and the casing 15 forms the space into which the products from the lamp casing 10 are discharged. To this end the lamp casing 10 at about its middle is connected to the interior of the casing 22 by means of a pipe section 26 which opens into

the space defined by the walls 23 and 24 85 below the pipe 16. The pipe 16, therefore, acts to deflect the fumes that may pass out of the casing 10 and causes the fumes to pass around in the space 22^a over the top of the casing 15 and so down and out as illustrated 90 in Fig. 2.

In order to provide for filling the water tank 13, I provide a filling pipe 27 which extends down through the top of the casings 22 and 15 and into the water tank. This 95 filling pipe 27 is normally closed by a removable cap 28. In order to provide for draining the tank, the tank 13 at its lower end is provided with an outwardly extending drain pipe 29 extending out through 100 the casings 15 and 22 and provided with a tap 30. In order to eliminate pressure due to expansion of water within pipe 14, I attach to the pipe 14 the vent pipe 31 which extends rearward through the pipe 16 or 105 flue, upward through the top of the casing 22. The lamp 33 may be of any suitable form and is supported beneath the chimney 11 in a manner illustrated in Fig. 1 and is connected to any suitable reservoir 35.

110 The operation of my invention will be obvious to those skilled in the art. In use

the tank 13 is filled with water to the proper height, as is the pipe system 14 extending therefrom. Inasmuch as the water pipe 14 is inclined upward, it will be obvious that the upper end of the pipe, that is, the end which is entered into the incubator, and the coils of pipe disposed within the incubator will be only half-filled with water. The lamp is then heated, which heats the water in the tank and in the pipe system leading therefrom and into the incubator. This hot water circulates through the coil in the incubator. At the same time fresh air is drawn in through the perforations 20 and 15 into the space 21 where it rises around the wall of the casing 10, then around the tank, and around the pipe 14, and thus passes into the incubator. Thus all the fresh air entering the incubator is warmed prior to its 20 entrance. The fumes from the lamp pass off through the pipe section 26 into the space 25 and circulate around the wall of the casing 15 and eventually pass out through the bottom of the heater between the walls 15 25 and 22.

It will be seen that no heat is wasted in this heater and further that the air which enters the incubator is uncontaminated by fumes. The heat is of course to be controlled by a suitable thermostat which is illustrated in the drawings and designated generally 34. I do not wish to be limited, however, to any particular form of thermostat. With my improved heater the incubator is heated by gentle warmth, and warm fresh air is continually entering the incubator and vitiated air is continually being carried out therefrom.

It will be seen that this construction provides a water heating plant for incubators very simple in operation and so certain in its action that it is no more trouble to run and operate in connection with an incubator or brooder than it is to operate a heater using hot air alone for the heating agency. The advantages of using a hot water heating system in place of a hot air heating system is that should the fire go out in a hot air machine the temperature of the incubator or brooder will drop instantaneously with disastrous results. With hot water as the heating medium, when the lamp goes out, that is, if it should go out, it will require hours for the machine to become chilled sufficiently to endanger the eggs in the incubator. I have found in practice that it is only necessary to fill the tank 13 once for a hatch. A further advantage of this heater is that the air used for ventilation is heated before it enters the incubator. This warm fresh air is carried into the top of the incubator by the natural current set up through the heated water pipe 14 and then the heated fresh air works its way down through the incubator into the egg

trays and nursery, taking off the foul air with it as it passes off at the outlet ducts usually found in each corner of incubators.

The vent 26 in the lamp chamber is so located that the lamp burns freely and will actually carry a larger flame when the lamp is disposed with its chimney in the lamp chamber than when the lamp is outside of the lamp chamber. The air passing up through the burner passes through vent 26, 75 circulates entirely around the casing 15, and eventually passes off at the bottom of the casing 24. The water pipe 14 extends upward at such an angle that when the heater is full of water the pipes inside the incubator are not over one-half full of water. When the water heats, the heat circulates through the pipes and assists in heating the incubator much better than when the pipes are completely filled with water. All liability of pressure on the pipes is eliminated by means of the vent pipe 31. This is also assisted by the fact that at no time are the pipes within the incubator or the pipe 14 entirely filled with water. In actual test 80 with a 200-egg incubator, this machine was operated 21 days on two gallons of oil worth about 30c.

Having described my invention, what I claim is: 95

1. An incubator heater comprising a centrally disposed lamp chamber, a water heating tank disposed above the lamp chamber and having a laterally extending pipe, a casing surrounding the lamp chamber and tank inclosing a fresh air heating chamber, a fresh air conduit leading therefrom and surrounding the water pipe, and a casing surrounding the fresh air chamber, spaced therefrom and having a discharge opening, and a pipe connecting the lamp chamber with the interior of said casing. 100

2. An incubator heater comprising a centrally disposed lamp chamber, a water heating tank disposed above the lamp chamber and having a laterally extending pipe, the bottom of the water heating chamber and the top of the lamp chamber being formed of a single septum, a casing surrounding the heating chamber and tank and in spaced relation thereto and inclosing a fresh air chamber open at its lower end and closed at its upper end, a fresh air conduit leading therefrom and surrounding the water pipe, and a casing surrounding the fresh air chamber and spaced therefrom and extending a distance along the fresh air conduit, the casing being open at its bottom and closed at its top, a pipe leading from the lamp casing into the lower portion of said last-named casing, and means for filling and draining the water tank. 115

3. An incubator heater comprising a centrally disposed lamp chamber, a water heating tank disposed above the lamp chamber, 130

the bottom of the tank forming the top of the lamp chamber and said tank having a laterally extending pipe, a casing surrounding the lamp chamber and tank, open at its bottom for the admission of fresh air and closed at its top and forming a fresh air chamber, a fresh air conduit leading therefrom surrounding the water pipe, said conduit being rectangular in cross section, and 5
10 a casing surrounding the fresh air chamber but spaced therefrom and closed at its top but open at its bottom, said casing having parallel extensions or parallel walls extending on each side of and in proximity to the 15 side of the air conduit, the space inclosed by said walls being closed at the top and open at the bottom, a pipe leading from the interior of the lamp chamber into the lower portion of said extended part of the outer 20 casing, a filling pipe extending from the tank upward through both of said casings, a cap detachably closing the filling pipe, a tap extending from the tank outward through both of said casings, and a vent pipe 25 connected to the water pipe and extending upward through the outer casing.

4. In an incubator heater of the character described, a lamp casing, a water tank supported thereon and having a laterally extending water pipe adapted to enter an incubator, a fresh air casing surrounding the lamp casing and the tank and spaced therefrom and having a laterally extending conduit surrounding the water pipe, an outer 30 casing surrounding the last-named casing and spaced therefrom to form a chamber wherein the fumes from the lamp chamber may circulate and connected to said lamp chamber and having a discharge opening, a 35 filling pipe extending through both of said casings into the water tank, a perforated an- 40

45 nulus disposed between the water tank and the first-named casing and surrounding said filling pipe, and a vent pipe leading from the water pipe.

5. The combination with an incubator having a side wall, of a heater therefor comprising a centrally disposed lamp chamber, a tank extending across the upper end of the lamp chamber and having a laterally 50 disposed pipe extending into the incubator, a casing surrounding the lamp chamber and the tank but terminating short of the lower end of the lamp chamber and being formed with perforations at its lower end for the 55 entrance of fresh air, said casing closing the fresh air heating chamber, a conduit rectangular in cross section extending from the upper end of the fresh air heating chamber and surrounding said pipe, said conduit 60 passing through the wall of the incubator, and an outer casing surrounding the fresh air heating chamber, extending over the top thereof but terminating short of the lower end of the fresh air heating chamber, said 65 casing having lateral walls extending therefrom and disposed in proximity to the side walls of the air conduit, the lower end of the space formed by said extensions being open, said extensions being flanged and the 70 flanges bearing against the wall of the incubator and attached thereto, and a pipe extending from the lamp chamber into the lower end of the space defined by said extensions.

75 In testimony whereof I hereunto affix my signature in the presence of two witnesses.

CLAUDE NUTTER.
